CLAIM

We claim the ornamental design for a cooler, as shown and described.

DESCRIPTION

FIG. 1 is a top front right side perspective view of a showing our new design;

FIG. 2 is a right side elevational view thereof, the side opposite being a mirror image;

FIG. 3 is a front elevational view thereof; and,

FIG. 4 is a top plan view thereof.

The broken lines in all views are for illustrative purposes only and form no part of the claimed design.
